MACHINE FOR MAKING OPEN BOXES

Henry B. Thompson, Jenkintown, Pa., assignor to
 Peter Paul, Inc., Naugatuck, Conn., a corpora-
 tion of Delaware

Application June 18, 1938, Serial No. 214,470

4 Claims. (Cl. 93—51)

This invention relates to a machine for making or forming open boxes or receptacles.

More specifically stated, the invention relates to an automatic machine for folding blanks into open receptacles or boxes.

The invention has for its salient object to provide a simple, practical and efficient machine for forming open boxes or receptacles from blanks.

Another object of the invention is to provide a machine of the character described having relatively few parts that can be economically manufactured.

Another object of the invention is to provide a machine of the character described so constructed and arranged that it can be easily and quickly adapted for making boxes of different sizes and dimensions.

Another object of the invention is to provide in a machine of the character described, simplified blank folding and box forming mechanism.

Further objects of the invention will appear from the following specification taken in connection with the drawings which form a part of this application, and in which

Fig. 1 is a side elevation of a machine constructed in accordance with the invention, the blank and supporting mechanism being omitted;

Fig. 2 is a top plan view of the structure shown in Fig. 1;

Fig. 3 is an end elevation of the structure shown in Fig. 1, this view being taken at right angles to Fig. 1;

Fig. 4 is a detail sectional elevation through the blank supporting and feeding mechanism and the forming plate for forming the blanks into boxes or receptacles;

Fig. 5 is a top plan view of the structure shown in Fig. 4;

Fig. 6 is a sectional elevation taken substantially on line 6—6 of Fig. 4;

Fig. 7 is a sectional elevation taken substantially on line 7—7 of Fig. 4;

Fig. 8 is a perspective view of the forming block or plate which forms the blanks into receptacles as they are pushed downwardly therethrough;

Fig. 9 is a top plan view of the forming block;

Fig. 10 is an end elevation taken at right angles to Fig. 9;

Fig. 11 is a transverse sectional elevation taken substantially on line 11—11 of Fig. 9;

Fig. 12 is an exploded view of the parts which comprise the forming block;

Fig. 13 is a longitudinal sectional elevation taken substantially on line 13—13 of Fig. 9;

Fig. 14 is a top plan view of a portion of the receptacle chain, illustrating the various positions of movement in which the folding of the receptacles is completed, the receptacles are filled and the filled receptacles are discharged;

Fig. 15 is a detail sectional elevation of the mechanism for completing the folding of the receptacle.

Fig. 16 is a perspective view of the box or receptacle as it is discharged from the forming block to the feed chain mechanism;

Fig. 17 is a perspective view of the completed box; and

Fig. 18 is a perspective view of the loaded receptacle.

The invention comprises a plurality of mechanisms including means for feeding blanks, means for forcing the blanks through a forming block or plate by which the blank is folded into an open receptacle or box, and means for completing the folding of the end flaps.

The blank feeding mechanism is so constructed and arranged that the various parts may be adjusted to provide for the feeding of blanks of different sizes and dimensions.

The forming plate or block through which the blanks are pressed and by which the blank is folded into an open receptacle has its various parts so relatively constructed and arranged that the side flaps and end tabs will be folded upwardly and inwardly and the end flaps will be folded upwardly and over the upper ends of the end tabs in one operation. The blank thus folded or the receptacle thus formed then moves to another position in the position of movement of the receptacle feeding chain, in which latter position mechanism is provided for completing the folding of the end flaps into their final position within the receptacle.

Further details of the invention will appear from the following description.

In the embodiment of the invention illustrated, the frame of the machine has a bed plate 25 which is provided with downwardly extending flanges 26, 26 and 27, 27.

Main driving connections

The main driving shaft 28 is mounted in the downwardly extending side frame members or flanges 27, 27 and is driven from any suitable source of power, as by a pulley 29.

The shaft 28 has mounted thereon a disk 30

50

55

having a pin or roller 31 at the outer end thereof adapted to enter and coat with notches 32 in a Geneva wheel 33 mounted on a shaft 34 supported in the flanges 21, 27 and disposed parallel to the shaft 28.

The shaft 34 has also mounted thereon worm wheels 35 and 36 which mesh with worm wheels 37 and 38 mounted on vertical shafts 39. Shafts 39 have secured to the upper ends thereof sprocket wheels 40 and 41 which drive feed chains 42 and 43 which feed the receptacles through the machine and operate in a manner hereinafter set forth.

The shaft 28 has also mounted thereon a sprocket wheel 45 which is connected by a sprocket chain 46 to drive a sprocket wheel 47 mounted on a shaft 48 which in turn is mounted in one of the flanges 27.

The shaft 48 is connected to drive a shaft 49 through bevel gears 50 and 51 carried respectively by the shafts 48 and 49. The shaft 49 is mounted in brackets 52 carried by one of the flanges 27. Shaft 49 has also secured thereto a sprocket wheel 53 which is utilized in a manner hereinafter described to drive the blank feeding mechanism.

Blank supporting and feeding mechanism

The blank supporting and feeding mechanism is illustrated particularly in Figs. 3-7 inclusive. The blanks X are supported on a plate 55 which is slidably mounted on rollers 56 and is reciprocatable to feed the blanks one at a time to a pair of coacting feed rollers 57 and 58.

The blanks X, as shown particularly in Fig. 5, are supported between vertical posts 60, 60 and 61, 61. The posts 61 are adjustably mounted by means of slots 62, 62 and pins 63, 63, the slots being formed in walls or vertical plates 64 mounted on a bracket 79 secured to the bed plate 25. The posts 60 are also secured to the walls or plates 64. By providing for the adjustment of the posts 61, 61 with reference to the posts 60, 60, provision is made for supporting and holding blanks of different lengths. If desired, the posts may also be made adjustable laterally to provide for different widths of blanks.

The bottom blank of the pile of blanks is fed forward on each forward movement of the blank supporting plate 55 in the following manner: The supporting plate is slidably mounted between the vertical walls or plate 64, as shown particularly in Figs. 6 and 7. The plate 55 has formed therein downwardly extending recesses 65 and 66, in which are mounted adjustable blocks 67 and 68. Each block is carried by a pin 69 and can be tilted by adjustment of set screws 70 and 71. After the blocks 67 and 68 have been adjusted to feed a blank of any required thickness, no further adjustment is needed until a blank having a different thickness is to be fed.

The blocks 67 and 68 engage at their front edges the rear edge of the lower blank when the plate 55 has been retracted to its extreme position and moves forwardly on its feeding movement.

The posts 60 can be vertically adjusted by means of the pin and slot connection 72 and 73 shown in Fig. 4, so that the bottoms of these posts will be spaced from the upper surface of the plate 55 a sufficient distance to permit the passage of a blank.

The reciprocation of the feeding and supporting plate 55 is accomplished in the following manner: The plate 55 has secured to the upper surface 75 thereof near the rear end of the plate a block

75 having a vertical and downwardly extending notch or recess 76 therein.

A shaft 77 is rotatably mounted in blocks 78 slidably mounted in walls 64 which in turn are mounted on the bed plate 25 and the bracket 79. The shaft 77 has mounted thereon a sprocket wheel 80 which is driven by a chain 81 from the sprocket wheel 53 carried by the shaft 49.

The shaft 77 has also mounted thereon an eccentric 82 which is disposed in an eccentric box 10 or yoke 83 which forms a part of a lever 84 mounted on a pivot 85. The blocks 78 are vertically adjustable by means of bolts 86 and are locked in adjusted position by lock nuts 87. It will be obvious that as the blocks 78, shaft 77 and eccentric 82 are vertically adjusted by raising or lowering the blocks 78, that the movement of the lever 84 by the eccentric 82 will be varied, thus a variable throw is provided to take care of different lengths of blanks.

The eccentric yoke or box 83 has threaded to its lower end thereof a post 88 having a ball 89 at the bottom thereof disposed in the recess 76 of the block 75. This threaded post 88 provides a micrometer adjustment for the throw of the blank feeding mechanism.

From the showing in Figs. 16 and 17 and also from the showing in Fig. 5, it will be seen that the blank X comprises a central or body portion A, side flaps B and C which are hinged to the body portion, each of the side flaps having disposed at its ends end tabs D and E.

There are also connected to the central or body portion A, end flaps F and G, the end flaps being divided into sections 90, 91 and 92. The sections 92 project laterally from the main body portion of the flaps F and G or are flared, as shown at 93.

When the blanks are supported for feeding movement the end tabs D and E are disposed between the vertically extending posts 60 and 61. Furthermore, the end flaps F and G extend rearwardly between the posts 61, 61 and forwardly between the posts 60, 60.

As the blanks are fed forwardly one at a time, the front end of the fed blank will be engaged by the pair of feed rollers 57 and 58 mounted on shafts 97 and 98. A shaft 99' has secured thereto a sprocket wheel 99 which is driven by the chain 81 which also drives the sprocket wheel 80.

The shaft 99' also has secured thereto a gear 100 which meshes with a gear 101 on the shaft 97 and drives the roller 57. Gear 101 also drives a gear 98' mounted on the shaft 98 and thus drives feed roll 58.

Blank folding or box forming mechanism

The forming plate or block through which the blanks are fed downwardly to the box feeding chain is illustrated particularly in Figs. 8-13 inclusive. The block comprises a pair of body members or side members 105 and 106 which are connected at their ends by end body members 107 and 108. The inner walls of the members 105 and 106 are beveled or inclined, as shown at 109, and the end walls 107 and 108 are also beveled or inclined, as shown particularly in Fig. 13 at 110.

The members 105 and 106 have secured to the upper surfaces thereof plates 111 and 112 and have also secured above the plates 111 and 112 members 113 and 114 having horizontal flanges or overhanging portions 115 and 116 which form grooves 117 and 118 above the plates 111 and 112.

As the blanks are fed forwardly by the feed

rollers 57 and 58, the lateral edge portions move into the grooves 117 and 118 of the forming blocks. The ends of the flanges 115 and 116 which receive the blanks are curved or flared, as shown at 119, and are also curved downwardly, as shown at 120 in Fig. 10.

The end body portion 108 has mounted on the upper surface thereof a pair of blocks 121 and 122 which are pivoted on the member 108 and are held in adjusted position by screws 123. The inner ends 124 of the blocks 121 and 122 are so adjusted as to engage the front edges of the front tabs E, E when the blanks are fed by the feed rolls 57 and 58 into the grooves 117 and 118 of the forming blocks.

The lower ends of the side members 105 and 106 of the forming blocks are notched, as shown at 125, to permit the downward passage of the blanks and not interfere with the passage of the flared ends of the end flaps F and G. When the blanks are positioned on the forming plate or block for downward movement therethrough and through the opening 126, the end tabs E, E are disposed on ledges 127, 127 and the end tabs D, D are disposed on ledges 128, 128. When the blank is so positioned the central portion A thereof is engaged by a plunger 130, (see Fig. 4), and the downward movement of the plunger causes the end tabs D and E to fold upwardly and causes the side flaps B and C to also fold upwardly. Furthermore, the end flaps F and G will be folded upwardly by engagement with the inclined surfaces 110, 110. The notches 125 will permit the downward passage therethrough of the flared ends of the end flaps F and G.

When the blank has been forced downwardly through the central opening 126 in the forming block, the blank will be folded to the position shown in Fig. 16.

The plunger 130 which feeds the blanks downwardly into the receptacle feeding chain is carried by a vertically slidable rod 131 which is slidably mounted in a bracket 132 carried by a vertical frame 133. The upper end of the rod 131 is connected by a link 134 to an arm 135 which is carried by a shaft 136 mounted to oscillate in the frame 133. The shaft 136 also has mounted thereon a gear 137 which meshes with a gear 138 carried by a shaft 139 also rotatably mounted in the frame 133. The shaft 136 has secured thereto an arm 140 which is connected to a link 141. The link 141 has formed or secured on the lower end thereof an eccentric yoke 142 in which is positioned an eccentric 143 mounted on the shaft 28. As the eccentric rotates the yoke and link 141 will be actuated thereby, thus oscillating the arm 140, shaft 136 and gears 138 and 137. As the gear 137 is oscillated the shaft 136 will also be oscillated, thus actuating the arm 135 to raise and lower the plunger 130.

The shaft 139 has also secured thereto an arm 145 which is connected by a link 146 to a cross head or bar 147. The bar 147 has secured thereto and extending downwardly therefrom three vertical posts 148, 149 and 150, the purpose of which will be hereinafter described.

70 Receptacle feeding chain

This construction is particularly illustrated in Fig. 14 and the driving connections therefor are shown in Fig. 2.

75 The feeding chains 42 and 43, as above stated,

are driven by sprocket wheels 40 and 41 mounted on the shafts 39, 39. These chains are guided into parallel relation with each other around idler sprocket wheels 155 and 156 which are adjustably mounted in the slots 157 in the bed plate 25. 5 The chains are guided at the other ends of their parallel paths of movement by means of idler sprocket wheels 158, 158 slidably mounted or adjustably mounted in slots 159.

From the sprocket wheels 158, 158 the chains 10 pass around a pair of idler sprocket wheels 160, 160 also adjustably mounted in slots 161. From the sprocket wheels 160, 160 the chains pass on the return lap to the sprocket wheels 40, 41.

Each of the chains 42, 43 has secured to its 15 links a plurality of blocks 163 and each block has a plate or web 164 formed thereon. The blocks and webs are so relatively located on the two chains that a web 164 on one chain will be 20 disposed opposite a web 164 on the other chain and the two adjacent webs on one chain will form with the two adjacent webs on the other chain a rectangular enclosure or pocket for receiving the folded receptacles, as shown in Fig. 14.

Thus, when the blanks are forced downwardly 25 through the forming block they will pass into successive enclosures or rectangular receiving and guiding portions of the feeding chains.

The adjustments for the various idler sprocket 30 wheels above described are provided for the purpose of changing the spacing of the chains relative to each other so as to receive receptacles of different lengths.

It will be understood that the chains 42 and 43, 35 as they move around their paths, are disposed with their webs 164 disposed adjacent the upper surface of the bed plate of the machine so that the receptacles will be pressed downwardly into the feeding chains and will be supported by the bed plate during the feeding movement thereof. 40

End flap folding mechanism

The completion of the folding of the end flaps is accomplished in the following manner: As shown particularly in Figs. 14 and 15, a pair of 45 plates 165 and 166 is mounted above the parallel laps of the chains 42 and 43, these plates having inclined edges 167 at the entering ends thereof.

When the receptacle has been formed by the 50 passage of a blank through the forming block and has been pressed into one of the chamber receiving closures, as shown at Y in Fig. 14, the end flaps will be disposed in the position shown.

The feeding chains operate intermittently by 55 reason of the feed derived from the Geneva wheel and as the chain advances the end flaps F and G will be engaged by the inclined edges 167 of the plates 165 and 166 and will pass beneath the plates in the manner shown particularly in Fig. 15.

When the feeding chains have advanced the receptacles to the position shown at R in Fig. 14, the posts 150 will be depressed and the ends 170 and 171 of a yoke 172 carried by the lower end of the post or rod 150 will engage the end flaps F 65 and G and will press them downwardly so that the end flaps will engage the inner surfaces of the folded tabs D and E and will form the inner end walls of the receptacle. Furthermore, the lower ends of the yoke ends 170 and 171 will cause the 70 end sections 92, 92 to be folded at right angles to the sections 91, 91 and against the bottom of the receptacles.

The flared ends or projections 93 on the lateral edges of the flaps F and G will frictionally engage 75

the inner surfaces of the side walls of the receptacle and will thus hold the end flaps in folded condition.

In order to provide a slight friction on the loaded receptacle after it reaches the position T and to prevent its dropping by gravity into the discharge chute, a spring pressed plunger 200 is slidably mounted in a guideway 201 and is resiliently actuated by a spring 202 to engage the front wall of the loaded receptacle disposed at the position T. The spring 202 can be adjusted to any desired tension by an adjustment shown at 203.

From the foregoing specification it will be seen that simple, practical and efficient automatic mechanism has been provided for feeding the blanks, folding the blanks into open receptacles, and completing the folding of the end tabs.

Furthermore, in the mechanism above described, provision has been made for adjustment so that blanks of different sizes can be handled. Moreover, particular attention is called to the fact that the blanks fed to the forming block are folded into open receptacles by one operation, thus eliminating the usual complicated folding arms and folding mechanism used to form the several folds necessary to fold the blanks into the receptacles.

Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims.

What I claim is:

1. In a machine for folding blanks having a central bottom forming portion, end flaps at the ends of said portion, side flaps at the sides of said portion and end tabs at the ends of said side flaps, a forming block having an opening for receiving said central portion and stationary folding forms surrounding said opening and so disposed as to successively fold the end tabs upwardly, fold the side flaps up at right angles to the central bottom portion and the end tabs inwardly and to fold the end flaps upwardly at right angles to the bottom portion to form receptacles open at the top and outside the end tabs, and means for feeding the blanks, one at a time through said block opening.

2. In a machine for folding blanks having a central bottom forming portion, end flaps at the

ends of said portion, side flaps at the sides of said portion and end tabs at the ends of said side flaps, a forming block having an opening for receiving said central portion and stationary folding forms surrounding said opening and so disposed as to successively fold the end tabs upwardly, fold the side flaps up at right angles to the central bottom portion and the end flaps upwardly at right angles to the bottom portion to form receptacles open at the top and outside the end tabs, means for feeding the blanks, one at a time through said block opening, receptacle feeding mechanism including pockets for receiving and feeding the receptacles, means above the path of movement of the receptacles for folding the end flaps inwardly above the receptacles, and means above the path of movement of the receptacles for forcing the end flaps downwardly into the receptacles and inside the end tabs.

3. In a machine for folding blanks having a central body portion, end flaps on the body portion, side flaps and end tabs on the side flaps into open receptacles, a forming block having fixed portions so constructed and arranged as to successively cause the side flaps to fold upwardly, the end tabs to fold upwardly and inwardly and the end flaps to fold up outside the end tabs when the blank is forced downwardly through the block, receptacle feeding mechanism including pockets for receiving and feeding the receptacles, means above the path of movement of the receptacles for folding the end flaps inwardly above the receptacles, and means above the path of movement of the receptacles for forcing the end flaps downwardly into the receptacles and inside the end tabs.

4. In a machine for folding blanks having a central body portion, end flaps on the central portion, side flaps and end tabs on the side flaps into open receptacles, a forming block having a central opening to receive said blank body portion, inclined surfaces at the ends of said opening to receive and fold the end flaps, inclined surfaces at the sides of the opening to receive and fold the side flaps, ledges at the sides of the end inclined surfaces for supporting the end tabs and causing the end tabs to be folded upwardly and inwardly as the blank is forced downwardly and before the end flaps are folded, whereby the end flaps are disposed outside the end tabs in the open ended receptacle, means for feeding blanks and means for engaging the blanks from above and forcing the blanks through the forming block.

HENRY B. THOMPSON.
